W. CAVE.
SURFACE CULTIVATOR.
APPLICATION FILED SEPT. 18, 1915.

1,171,927.

Patented Feb. 15, 1916.

W. GAVE Inventor

By Watson E. Coleman

Attorney

UNITED STATES PATENT OFFICE.

WILLIAM CAVE, OF NEWELL, IOWA.

SURFACE-CULTIVATOR.

1,171,927.

Specification of Letters Patent. Patented Feb. 15, 1916.

Application filed September 18, 1915. Serial No. 51,395.

To all whom it may concern:

Be it known that I, WILLIAM CAVE, a citizen of the United States, residing at Newell, in the county of Buena Vista and State of Iowa, have invented certain new and useful Improvements in Surface-Cultivators, of which the following is a specification, reference being had to the accompanying drawings.

10 This invention relates to certain improvements in surface cultivators of a wheeled type and has relation more particularly to a device of this general character wherein both knives and rakes are employed; and it 15 is an object of the invention to provide novel and improved means whereby a knife and a coacting rake may be operatively engaged with the machine in such a manner as to permit a convenient adjustment of the pitch of 20 the knife and an adjustment of the rake relative to the row.

The invention consists in the details of construction and in the combination and arrangement of the several parts of my improved surface cultivator whereby certain 25 important advantages are attained and the device is rendered simpler, less expensive and otherwise more convenient and advantageous for use, all as will be hereinafter 30 more fully set forth.

The novel features of the invention will be carefully defined in the appended claims.

In order that my invention may be the better understood, I will now proceed to describe the same with reference to the accompanying drawings, wherein—

Figure 1 is a view in perspective illustrating an embodiment of my invention, the coacting portion of a cultivator being shown 40 in fragment; and Fig. 2 is a detail fragmentary sectional view illustrating certain features of my invention as herein embodied.

As disclosed in the accompanying drawing, H denotes a head of the type employed 45 in the well known tower two-row cultivator, the rear extremity of which being provided with an opening 1 therethrough in which is adapted to be inserted from above the angular extremity 2 of the arm A, said extremity being preferably disposed at right angles to the arm. Also insertible within the opening 1 of the head H is the upstanding boss 3 carried by an extremity of the arm B, said boss being adapted to have disposed therethrough the headed bolt 4 adapted 50 for detachable engagement with the an-

gular extremity 2 of the arm A and whereby it will be perceived that the arms A and B will be operatively engaged with the head H. The outer extremities of the arms A 30 and B terminate in the annular members or eyes 5 between which is adapted to be positioned the annular member or eye 6 of the arm C and through said annular members or eyes 5 and 6 is adapted to be disposed the 35 shank S of the surface knife K of well known type. The annular members or eyes 5 and 6 have threaded therethrough the clamping screws 7 whereby an effective engagement is had with the shank S. 70

It is to be observed that the arm B comprises two sections 8 and 9, the adjacent extremities whereof being in overlying relation and one of said sections is provided with the longitudinally disposed slots 10 75 through which is adapted to be disposed the clamping bolts 11 carried by the section 8. By this arrangement, it will be seen that the arm B may be lengthened or shortened in accordance with the pitch desired to be 80 given to the knife K.

12 denotes an elongated arm having one extremity pivotally engaged with the head H intermediate the length thereof and having its opposite extremity underlying the arm C normally disposed laterally relative to the arms A and B, and said arm C is provided with the longitudinally disposed elongated slot 14 through which is disposed one of the clamping bolts 15 for operatively 90 engaging the rake R with the arm 12, said rake R being also of a well known type. By the provision of the elongated slot 14 in the arm C, it will be readily observed that the position of the rake relative to a row may 95 be adjusted as will best meet the requirements of practice.

It is also preferable to have operatively engaged with the head H, in a well known manner, a forward knife K'.

From the foregoing description, it is thought to be obvious that a surface cultivator constructed in accordance with my invention is of an extremely simple and comparatively inexpensive nature and is particularly well adapted for use by reason of the convenience and facility with which it may be assembled, and it will also be obvious that my invention is susceptible of some change and modification without material departure from the principles and spirit thereof and for this reason I do not 105 110 115

wish to be understood as limiting myself to the precise arrangement and formation of the several parts herein shown in carrying out my invention in practice.

5. I claim:

1. In combination with a cultivator including a head provided with an opening therethrough, an arm having an angular extremity disposed within said opening, a second arm having a lateral extension disposed within the opening through the opposite side of the head, both of said arms being arranged substantially parallel to the line of draft, means coacting with the extensions of the arms for maintaining said arms operatively engaged with the head, and a ground engaging implement operatively supported by the outer extremities of the arms.
10. 2. In combination with a cultivator including a head provided with an opening therethrough, an arm having an angular extremity disposed within said opening from one side of the head, a second arm having a lateral extension disposed within the opening through the opposite side of the head, means coacting with the extensions of the arms for maintaining said arms operatively engaged with the head, and a ground engaging implement operatively supported by the outer extremities of the arms, one of said arms being capable of longitudinal adjustment.
15. 3. In combination with a cultivator including a head provided with an opening therethrough, an arm having an angular extremity disposed within said opening from one side of the head, a second arm having a lateral extension disposed within the opening through the opposite side of the head,

means coacting with the extensions of the arms for maintaining said arms operatively engaged with the head, a ground engaging implement provided with a shank operatively engaged with the outer extremities of the arms, a third arm operatively engaged with the shank of the ground engaging implement and disposed laterally relative to the first named arms, a bar pivotally engaged with the head and adjustably engaged with the third mentioned arm, and a rake engaged with said arm.

4. In combination with a cultivator including a head provided with an opening therethrough, an arm having an angular extremity disposed within said opening from one side of the head, a second arm having a lateral extension disposed within the opening through the opposite side of the head, means coacting with the extensions of the arms for maintaining said arms operatively engaged with the head, a ground engaging implement provided with a shank operatively engaged with the outer extremities of the arms, a third arm operatively engaged with the shank of the ground engaging implement and disposed laterally relative to the first named arms, a bar pivotally engaged with the head and adjustably engaged with the third mentioned arm, a rake, and means for securing said rake to the bar, a portion of said means serving to connect the bar with the third mentioned arm.

In testimony whereof I hereunto affix my signature in the presence of two witnesses.

WILL CAVE.
